UNITED STATES PATENT OFFICE.

CHARLES E. RICHARDSON, OF NEWARK, NEW JERSEY, ASSIGNOR TO INTERNATIONAL COAL PRODUCTS CORPORATION, OF RICHMOND, VIRGINIA, A CORPORATION OF VIRGINIA.

FURNACE-RETORT.

Application filed August 2, 1919. Serial No. 314,887.

To all whom it may concern:

Be it known that I, CHARLES E. RICHARDSON, a citizen of the United States, and a resident of Newark, in the county of Essex and State of New Jersey, have invented certain new and useful Improvements in Furnace-Retorts, of which the following is a specification.

The invention relates to a furnace-retort 10 and particularly to a type wherein coal or similar carbonaceous material is subjected to a distilling or carbonizing operation in order to produce, for example, a partially carbonized residue.

The present invention is based upon a furnace-retort construction having a retort into which the coal is fed at one end, wherein the coal is agitated or mixed and conveyed along the retort to the other or discharge end and from which discharge end the partially carbonized residue leaves the retort. The furnace-retort comprehends a construction wherein the retort has a body portion preferably made of metal, and in the form of a longitudinally extending wall or retort shell, and wherein the furnace is constructed so as to provide a combustion space or spaces on the exterior of the body portion of the retort and is also provided with burners 20 constructed and arranged so as to facilitate a ready and easy control of the heat action on the retort shell.

The invention is directed to the manner whereby the longitudinally extending inner wall or retort shell is supported in or by the furnace construction, to the manner in which the furnace is constructed so as to permit a ready and easy assembling and disassembling of the several parts, especially in regard to the facilitating of the installing and removing of the retort portions, to the construction and arrangement of certain supports for locally supporting the retort shell, to the arrangement of the burners with respect to the rest of the furnace-retort construction, and to the flue arrangement within the furnace-retort construction whereby the products of combustion are conducted from the combustion space or spaces.

The invention, according to another aspect thereof, is directed to the manner in which a preheater is brought into association with the retort and particularly whereby the preheater is supported above but in-

dependently of the furnace-retort structure, thus preventing the latter from being subjected to any strains incident to the operation of the preheater.

The invention has in view the features above referred to and also others, all of which are illustrated and hereinafter clearly described.

As showing a specific manner in which the invention may be realized reference is made to the accompanying drawings forming a part of this specification and in which drawings,

Figure 1 is a vertical longitudinal sectional view of a furnace-retort with a preheater located above but supported independently of it. This figure is a view taken as on the planes indicated by the broken line 1—1 of Figures 2, 4 and 5 looking in the direction of the arrows. Within the retort or retort shell there are located two shafts each carrying paddles, this construction being clearly indicated in Figure 2. In Figure 1 only one shaft and the paddles thereupon are indicated, to wit, the shaft and the paddles where the section is taken.

Figure 2 is a vertical and transverse sectional view of the furnace-retort showing the supports for the preheater above it and also some of the piping or flue construction for conducting waste gases from the furnace of the furnace-retort to the preheater. This is a view taken as on the planes indicated by the broken line 2—2 of Figure 1 looking in the direction of the arrows. Figure 2 taken in conjunction with Figure 1 discloses the manner in which the products of combustion pass from the combustion space or chamber of the furnace-retort to the interior of the preheater.

Figure 3 is a vertical end view of the furnace-retort and preheater and is a view looking toward the charging end of the furnace-retort. Figures 1, 2 and 3 clearly show the manner in which the preheater is supported above but independently of the furnace-retort.

Figure 4 is a vertical transverse sectional view of the furnace-retort and is a view taken as on the planes indicated by the broken line 4—4 of Figure 1 looking in the direction of the arrows. The upper half of Figure 4 and particularly each side portion thereof shows a burner, located in a

vertical plane, which is intermediate local supports that are provided for and below the longitudinally extending wall or retort shell, while the lower half of said figure and 6 particularly the central portion thereof shows in section the local support construction.

Figure 5 is a vertical sectional view taken as on the plane indicated by the line 5—5 10 of Figures 1, 6 and 7 looking in the direction of the arrows and is a view showing the manner in which the products of combustion pass from the combustion space at each side of the furnace to a longitudinally extending 15 side flue within the walls of the furnace.

Figure 6 is a horizontal sectional view taken as on the plane indicated by the line 6—6 of Figures 2, 4 and 5 looking in the direction of the arrows. In Figure 6, however, 20 there is shown only that portion of the masonry and supporting structure which is on the exterior of and which is not included in and considered a part of the retort proper. In other words, the retort shell, the members 25 therein, and in fact all parts of the retort proper have been removed. Figure 6 has been inserted primarily to show the local supports at and along the bottom of the retort, to indicate the spaces between adjacent 30 local supports where the products of combustion can engage or have access to the bottom or lower exterior portion of the retort shell, and also to show the flue arrangement whereby the products of combustion are conducted 35 from combustion spaces at the sides of the retort shell, through the longitudinally extending side flue to a vertically extending waste heat flue in a side wall of the furnace-retort construction and which waste 40 heat flue conducts the waste gases or products of combustion from the furnace-retort.

Figure 7 is a horizontal sectional plan view taken as on the plane indicated by the line 7—7 of Figures 1, 2, 4 and 5 looking in 45 the direction of the arrows. In Figure 7 there is particularly indicated in plan the position of the members in the furnace-retort construction which have been provided to give the desired local support for the 50 retort shell and also to permit or take care of the expansion of the retort shell. Figure 7 should be considered in conjunction with Figure 6 as each of these figures shows some phase of the local support more clearly than 55 the other figure, or some phase not brought out in the other figure. As Figure 7 has been included to illustrate certain features of the local support construction many details relating to the paddle carrying shafts have 60 been omitted: neither are the paddles shown. Figures 1 and 4 show that each local support for the retort shell has a set of I-beams with a supporting plate resting thereupon, which plate is frequently referred to as a bottom 65 supporting plate, has a standard or central

supporting member on said plate, has a second or upper supporting plate, similar to that resting upon the set of I-beams but occupying an inverted position, and has a saddle upon the upper supporting plate, which 70 saddle locally carries or locally supports the inner wall or retort shell. There is, however, between each upper supporting plate and its corresponding saddle a layer of flat sheet asbestos and a layer of flat sheet copper for providing both a heat insulating joint and a sliding joint between these two members, to wit, between the upper supporting plate and the saddle. The construction 75 of the members just referred to, to wit, the supporting plates, the standard or central supporting member and their relative positions, is brought out in Figures 9 to 14 inclusive.

Figure 8 is a horizontal sectional view 80 taken as on the plane indicated by the broken line 8—8 of Figure 1 looking in the direction of the arrows and is a composite figure illustrating different portions of the structure. Portion *a* of this figure shows in section one 85 set of the I-beams of the local support, which I-beams extend horizontally and transversely. Portion *b* shows the construction through a bottom supporting plate and a standard or central supporting member 90 thereupon; this portion of the section is the same as if taken on the lines 8—8 of Figures 9 and 10 looking in the direction of the arrows. Portion *c* indicates different types of 95 layers of masonry designated respectively *d* and *e* and found between adjacent local supports. The layer *d* is of any material suitable 100 to provide a foundation or floor structure and layer *e* is of a material suitable for heat insulating purposes, or in other words 105 serves to insulate the layer *d* against heat that otherwise would pass to it from the interior of the furnace. Portion *f* shows the 110 construction through the standard or central supporting member; the masonry designated *g* in this section is of fire brick. Portion *h* indicates the joint between the upper supporting plate and saddle thereupon, which joint may be referred to as a heat insulating or break or sliding joint, according 115 to the aspect or view in which it is considered. Portion *k* shows a part of the combustion space between adjacent saddles, or in other words between the fire brick masonry 120 casings protecting the saddles. Portion *m* illustrates a section through the saddle at the charging end of the retort. The opening *n* at the opposite end shows in section the discharge passageway leading from the retort.

Figures 9 and 10 are longitudinal and 125 transverse sectional views showing the construction of the local supports for and below the retort shell.

Figure 11 is a perspective view of a supporting plate which serves, when in one po- 130

sition, as the bottom supporting plate that rests upon the top of a set of I-beams and upon which plate in turn rests the standard or central supporting member previously referred to and shown in Figure 12. In an inverted position the supporting plate shown in Figure 11 rests upon the top of the standard or central supporting member and serves when in said position as the upper supporting plate that carries the saddle.

Figure 12 is a perspective view showing, as previously indicated, the standard or central supporting member.

Figures 13 and 14 are side and bottom views of the saddle.

Referring now to the drawings in detail the furnace-retort is designated by 1 and there is located above but independently of it a coal preheater 2—known in the trade as the Ruggles-Cole dryer—which as will hereinafter appear has been employed to perform two functions, that of drying the coal as well as that of preheating the coal so as to introduce the coal into the retort in a dry heated condition. The retort proper is designated by 3 and the furnace proper by 4. The retort has a longitudinally extending inner wall or retort shell 5 and has at each end a suitable head, as 6 and 7, the head 6 being located at what is known as the charging end of the retort and the head 7 at the discharging end thereof. The material to be treated, to wit, such as bituminous coal or other similar carbonaceous material, is delivered from the pre-heater 2 by means of chute 8 into feeding means 9 which in the form illustrated is a screw-conveyer relied upon to feed the coal to the interior of the retort.

The retort has within the longitudinally extending wall or retort shell a pair of shafts, each designated by 10 and each carrying paddles or blades 11. The shafts are arranged so that the paddles on one shaft overlap the paddles on the other shaft and so that the paddles or blades cooperate to mix or agitate the charge within the retort and to convey the material being treated from the charging end of the retort toward the discharging end thereof. The shafts 10 extend through the heads 6 and 7 and there is provided suitable sealing means, as 12, for preventing the escape of gas from the interior of the retort and for opposing the entrance of air through the spaces between each head on the one hand and the corresponding end of the shaft on the other to the interior of the retort.

The furnace is constructed so as to exteriorly heat what may be referred to as the body portion of the longitudinally extending wall or retort shell, to wit, particularly the longitudinally extending bottom and side portions of the retort shell, and the vapors and gases driven off during this

heating are withdrawn by piping 13 leading to a hydraulic main 14 supported on transversely extending beams 15 that are in turn supported upon longitudinally extending girders or beams 16. The gases, vapors and tars are subsequently collected from the hydraulic main by suitable apparatuses well known in the art. The coal when fully treated, viz. when partially carbonized, is delivered from the interior of the retort, through the discharge passageway 17 past a suitable valve or sealing means 18 constructed so as to permit the discharge of the treated material from the retort without permitting the entrance of any substantial amount of air to the interior thereof.

The furnace-retort which is the basis of the present invention is particularly desired for the treating of coal in order to produce a uniformly but partially distilled residue and the heating is carried out while the shafts are being rotated and in a manner whereby this condition of the material is enabled to be realized.

The temperature within the retort usually approximates 850° F. although it will be appreciated that, dependent upon the character of the material being treated and the manner in which it is treated within the retort, this temperature can be varied. The longitudinally extending wall or retort shell is preferably made of metal, such as cast material half iron, half steel—frequently referred to as semi-steel—and in order that this retort shell will be properly supported there has been provided a number of spaced local supports 19, which are in fact spaced local supporting members and these local supports are arranged in a series extending longitudinally along the retort in a manner whereby the lower central portion of the longitudinally extending wall or retort shell receives local support in several places. The masonry portion of the furnace provides what may be referred to as a horizontally, longitudinally and transversely extending floor structure 20 within which the local supports are located, the vertically and longitudinally extending side walls 21, the longitudinally extending roof portion 22 and the vertically and transversely extending end walls 23. The longitudinally extending wall or retort shell is also preferably made in effect continuous from the charging end to the discharging end and the local supports allow for its contraction, due to cooling, as well as for expansion, due to heating.

In Figures 4 and 5, for example, it will be seen that in the upper portion of each side there is an arched portion 24 and this arched portion may in some respects be considered as a part of the side and in other respects as a part of the roof. The arched portion 24 is therefore sometimes referred to as side roof

members, as arched side members or as arched roof members. In the same figures it will also be observed that a combustion space or chamber 25 is provided between the 5 bottom and side portions of the longitudinally extending wall or retort shell on the one hand and between the bottom, side and arched side roof members of the masonry construction on the other. The arched roof 10 members 24 are each preferably constructed so as to have an arched shape casting 26 with an inwardly extending lip at the lower end thereof and with a downwardly extending lip at the upper end thereof whereby the 15 casting 26 can serve as a holder for the brick work in the arched shape section. These holder castings 26 also carry burners 27 whereby a homogeneous mixture of proportioned gas and air is projected downwardly 20 along the vertically extending inner portions of the side walls 21, thus producing a flame or zone of burning mixture which may take or have the form indicated by 28 in Figure 4. In other words, the flame or zone of 25 burning mixture follows the inner sides of the masonry but does not directly contact with the metallic longitudinally extending wall or retort shell. It will here be remarked that at the juncture of the longitudinally and transversely extending floor 30 structure 20 and each vertically and longitudinally extending side wall 21 there is a portion having an inner surface which extends downwardly and inwardly. This 35 downwardly and inwardly extending surface portion deflects the burning mixture or products of combustion downwardly and inwardly and facilitates the heating of the under side of the retort. These arch 40 shaped sections that are provided by the several arch shaped holder castings and bricks carried thereby may, as previously indicated, be considered as removable roof sections or removable side wall members 45 located at the tops of the side walls. Each of these sections constitutes a single removable member composed of a number of different units, to wit, a member composed of the holder casting, the burner carried there- 50 by, and the heat insulating and fire brick held together by the holder casting.

Reference has also been made to the supporting of the longitudinally extending wall or retort shell by the local supporting members 19. The supports 19 are separated from each other leaving spaces, as 29, whereby for 55 all exterior lower portions of the tubular inner wall or retort shell, except in the immediate vicinity of the supports 19, the products of combustion will have free access 60 to or will engage the under side of the tubular inner wall or retort shell for the full width thereof. The spaces 29 are clearly indicated in Figures 1, 2, 5 and 6. The gas 65 and air, each of which is respectively con-

sumed and relied upon to support combustion, are preferably forced into the combustion spaces 25 whereby combustion takes place in the manner outlined and the products of combustion fill the entire combustion space within the masonry construction and on the exterior of the retort shell. That portion of the masonry which defines the combustion spaces is of suitable refractory material, such as fire brick (see for example Figure 8, particularly designated by 9). 70

The products of combustion leave from one end of the combustion spaces, as through openings or passageways 30 (see particularly Figures 5, 6 and 8) then travel horizontally and laterally through passageways 31 into longitudinally extending waste gas ducts, flues or passageways 32 that are located in the side portions of the masonry construction—these flues 32 are sometimes referred to as longitudinally extending side flues. These flues 32 from one point of view may be considered as located in the floor construction, or from another point of view may be considered as located in the side walls; and it will here be remarked that the vertically extending side walls may be considered as merging into the floor structure or the floor structure may be considered as merging into the side walls. Within one of the side walls of the furnace-retort construction there is provided a vertically extending waste gas flue 33 into which one of the longitudinally extending side flues 32 in effect directly discharges and into which the other longitudinally extending side flue 32 discharges by means of a transversely extending conduit or passageway 34, clearly shown in Figures 2 and 6. 80

The particular form of retort shown is in cross-section in the form of a modified B positioned so that the curved portions of the B are at the bottom and so that the straight or back line of the B extends horizontally. This straight or back portion of the B indicates a part of the flat roof 35 of the retort shell. The roof is of sheet metal rolled plate that is suitably connected to the upright portions of the retort shell, as by welding along the line 36, and this flat roof 90 may also be locally reinforced, as by means of transversely extending angle irons 37. This flat roof 35 is covered by the masonry roof portion 22, previously referred to, which includes a layer of heat insulating material 38, such as a layer formed of brick or diatomaceous earth or the like. The roof has been made of masonry with this heat insulating material in order to heat insulate the retort from the direct cooling action of the exterior air and in order to maintain a more uniform heat condition within the retort; or, in other words, to hold the heat within the retort. In order to minimize the loss of heat from the side walls 100

105

110

115

120

125

130

and floor portion of the furnace, layers of heat insulating material are provided, such as 39, in the arched roof side members, 40 in the main portion of the side walls, and 41 in the floor structure. In Figure 8 part of the layer of heat insulating material is indicated by the letter *e*.

To permit of inspection along the retort, removable brick members, as 42, are provided, the position of these members being clearly shown in Figures 4 and 6 of the drawings.

Reference has heretofore been made to the local supports or supporting members arranged in series along the lower central portion of the longitudinally extending wall or retort shell. The arrangement of these local supports or supporting members is clearly shown in Figures 1, 6, 7 and 8 and the construction thereof is readily apparent from Figures 1, 4, 8 and 9 to 14 inclusive. From the figures just referred to it will be readily apparent that for each individual support there is provided a set of transversely extending I-beams 43—three I-beams in each set—resting upon a suitable base or foundation, as 44. The sets of I-beams of the different local supports are, as previously stated, arranged in series and the series extend longitudinally. In each support and upon the central portion of the set of I-beams therein there is located a bottom supporting plate or member 45 having grooved portions 46 within which there is seated the lower end of a standard or central supporting member 47. A flat top upper supporting plate or member 48, which is the same as the supporting plate or member 45 but inverted, rests upon the standard or central supporting member 47. A flat bottom saddle 49 is carried by but movably—that is slidably—mounted upon the upper supporting plate or member 48.

In the specific construction illustrated the saddle is, as previously indicated, slidably mounted upon the upper supporting plate or member 48. The sliding is facilitated by means of what may be considered as a break or sliding joint construction between the saddle and the supporting plate. This sliding joint construction comprises a layer of flat sheet asbestos that rests upon the upper supporting plate 48 and a layer of flat sheet copper that in turn rests upon the sheet of asbestos. The under side of the saddle is preferably provided with longitudinally and transversely extending grooves 50, although it will be readily appreciated that this grooving while advantageous is not necessary. Because of the inclusion of the layer of asbestos this sliding or break joint construction may also be referred to as a heat insulating joint. The longitudinally extending wall or retort shell may be considered in effect as fixedly secured at the charging end thereof

and the break or sliding joints have been provided in order to enable a differential expansion of the retort shell in reference to the masonry construction within which it is located and with reference to the fixed portion of the local supports upon which the retort shell bears. The longitudinally extending wall or retort shell rests directly upon the saddles 49 and in order that the saddles, plates and standards—all of which are of metal—will be protected against the heat or action of the products of combustion the masonry from the floor structure has been extended to the under side of the longitudinally extending wall or retort shell and in a manner to encircle or encase that portion of each local support which would otherwise extend into and be directly within the combustion space or spaces. In order that the metal portions of each local support will be cooled or prevented from being unduly heated, transversely extending open arched portions indicated by dotted lines in Figs. 1 and 7 have been provided in the masonry construction and this open arch allows the air to contact directly with all of the members of each local support, with the exception of the saddle and the layers of flat material between the upper supporting member and the saddle.

It has heretofore been pointed out how the products of combustion leave the furnace-retort construction through the vertically extending side or waste gas flue 33. In the construction as shown the products of combustion pass from said side or waste gas flue 33 through vertically extending flue portion 52, thence transversely through horizontally extending flue portion 53, thence longitudinally through horizontally extending portion 54 to the interior of the preheater 2, where they are employed for drying and preheating the coal within the preheater and whereby the coal can be conducted and fed to the retort from the preheater through and by means of chute 8 and feeding means 9 previously described. The preheater has a tubular receptacle or heating drum 55 that revolves when the preheater is functioning.

It will also be noted and particularly from an inspection of Figures 1, 2, and 3 that the preheater 2 is carried upon longitudinally and substantially horizontally extending beams 56 that are in turn supported above and independently of the furnace upon transversely extending beams 57 carried by columns 58. By this construction the likelihood of any detrimental effect being imparted to the furnace, due to vibrations on operating the preheater, is avoided. In other words, the preheater can be brought into association with the furnace-retort without fear of any damage being done to the latter as the result of operating the pre-

heater, while the advantageous results of charging a hot dry coal to the interior of the retort is realized.

- The furnace-retort which is the subject 5 of the present invention is adaptable for performing the initial or preliminary heating referred to in United States Patent No. 1,177,727 granted April 4, 1916, covering the invention of Charles H. Smith, entitled 10 Process of treating coal, for performing the heating of coal according to the manner outlined in United States Patent No. 1,224,424 granted May 1, 1917, covering the invention of Charles H. Smith, entitled 15 Process of and apparatus for treating coal; and for performing the initial distillation or preliminary carbonization referred to in United States Patent No. 1,276,429 granted August 20, 1918, covering the invention of 20 Charles H. Smith, entitled Briquet and method of making the same.

It will be manifest from what has preceded that the features of construction can be embodied in various forms and modifications without departing from the spirit 25 and scope of the invention.

What is claimed is:

1. A furnace-retort having a longitudinally extending inner wall or retort shell, 30 flat bottom saddles spaced from each other and arranged along the inner wall or retort shell and serving as supports therefor, a flat top saddle support for each saddle, and a layer of flat sheet copper and a layer of 35 flat sheet asbestos between each saddle and its support.

2. A furnace-retort having a longitudinally extending inner wall or retort shell, 40 saddles spaced from each other and arranged along the inner wall or retort shell and serving as supports therefor, a saddle support for each saddle, and a layer of copper and a layer of asbestos between each saddle and its support.

45 3. A furnace-retort having a longitudinally extending inner wall or retort shell, saddles spaced from each other and arranged along the inner wall or retort shell and serving as supports therefor, a supporting plate for each saddle, and a layer 50 of copper between each saddle and its supporting plate.

4. A furnace-retort having a longitudinally extending inner wall or retort shell, 55 saddles spaced from each other and arranged along the inner wall or retort shell and serving as supports therefor, a supporting plate for each saddle, and a layer of asbestos between each saddle and its supporting plate.

5. A furnace-retort having a metallic wall 60 or retort shell, and masonry construction providing a floor structure below but spaced from the retort shell and side walls at each 65 side of the retort shell, said masonry con-

struction having therein metal saddles and metal plates, each of which metal plates serves as a support for a corresponding saddle, there being between each saddle and its corresponding plate a heat insulating joint 70 comprising asbestos.

6. A furnace-retort having a metallic longitudinally extending wall or retort shell, and masonry construction providing a floor structure below but spaced from the retort shell and a side wall extending along each side of the retort shell, said masonry construction having therein metal saddles and metal plates, each of which metal plates 75 serves as a support for a corresponding saddle, there being between each saddle and its plate a break-joint or sliding joint comprising flat-faced copper and flat-faced asbestos arranged so that the flat face of one rests 80 upon a flat face of the other. 85

7. A furnace-retort having a substantially continuous metallic longitudinally extending wall or retort shell, and masonry construction providing a floor structure below but spaced from the retort shell and side 90 walls extending along the sides of the retort shell, said masonry construction having therein metal saddles and metal plates, each of which metal plates serves as a support for a corresponding saddle, and flat sheet masonry 95 between each saddle and its plate.

8. A furnace-retort mounted upon a suitable foundation, which furnace-retort comprises in combination transversely extending I-beams arranged in sets and resting upon the foundation, a bottom supporting plate upon each set of I-beams, a standard or central supporting member upon each bottom supporting plate, a top supporting plate resting upon each standard or central supporting member, a saddle suitably mounted upon each of said top supporting plates, a longitudinally extending retort shell seated upon said saddles, the saddles being spaced 100 from each other, and a masonry construction 105 which provides a floor structure extending along and below the retort shell, and also side walls and side roof members located along the retort shell whereby there is provided between the retort shell and the masonry construction a combustion space, the masonry construction being such that the saddles and supporting members are protected against the action of the products of 110 combustion. 115

9. A furnace-retort mounted upon a suitable foundation, which furnace-retort comprises in combination transversely extending I-beams arranged in sets and resting upon the foundation, a bottom supporting plate upon each set of I-beams, a standard or upright member upon each bottom supporting plate, a top supporting plate resting upon each standard or upright support, the upper surface of each of which top sup- 120 125 130

porting plates extends horizontally, a saddle upon each of said top supporting plates, a longitudinally extending retort shell seated upon said saddles, the saddles being spaced from each other, a masonry construction which provides a floor structure extending along and below the retort shell and also side walls and side roof members located along the retort shell whereby there is provided between the retort shell and the masonry construction a combustion space, the masonry construction being provided with suitable flues whereby products of combustion can be conducted from said combustion space, and burners for supplying a mixture of gas and air to that portion of the combustion space at each side of and below the retort shell.

10. A furnace-retort having a longitudinally extending retort shell of cast metal with a head at each end of the retort shell, shafts extending through the heads and carrying paddles shaped so as to mix and convey the material along the interior of the inner wall, means for feeding coal into the retort shell at one end thereof, there being a discharge opening or passageway at the other end through which the material is discharged from the retort, saddles spaced from each other and arranged along the retort shell to locally support the lower portion thereof, vertically extending side walls spaced from the retort shell and extending along the same, a floor structure which with the side walls provide a combustion space between them and the retort shell, portions of which space are below and extend the full width of the retort shell, and means for supplying gas and air to the upper portions of the combustion space, there being a longitudinally extending flue located in the lower portion of each of said side walls, one of said side walls also having therein an opening or passageway at each side through which products of combustion pass from the combustion space to the corresponding longitudinally extending flue, the furnace-retort also having openings or passageways that lead from said longitudinally extending flues into a vertically extending flue which is in one of the side walls.

11. A furnace-retort having a longitudinally extending retort shell having a cast metal body portion, masonry having a floor structure below the body portion, having side walls extending upwardly from the floor structure and along the body portion, and having an arched side roof member extending upwardly and inwardly from each side wall to said body portion whereby a combustion space is provided between said body portion on the one hand and the masonry on the other, and a heat insulating roof portion extending along the top of the retort shell and from the arched side roof

member at one side of the furnace-retort to the arched side roof member at the other side, the arched side roof members having castings serving as holders for the masonry portion of the side roof member and also having burners carried by the castings for supplying mixtures of gas and air to the combustion space.

12. A furnace-retort having a longitudinally extending retort shell, masonry construction providing a refractory floor extending below and along the retort shell and refractory side walls, each of which side walls has at the lower portion thereof a downwardly and inwardly extending inner surface portion and at the upper portion thereof an inwardly extending side roof portion reaching to the retort shell, the construction being such that a combustion space is provided between the retort shell and said masonry construction, masonry extending from the side roof portion at one side of the furnace-retort to the side roof portion at the other side for heat insulating the top of the retort shell, means for supplying a heating medium to the combustion space, supporting plates with flat horizontally extending tops arranged in spaced relationship below the retort shell, and a saddle for and movably supported on each plate for locally supporting the retort shell.

13. A furnace-retort having an inner wall or retort shell, and masonry providing a refractory floor extending below the inner wall or retort shell and refractory side walls, which side walls have at the lower portions thereof downwardly and inwardly extending inner surface portions and at the upper portions thereof inwardly extending side roof members, the construction being such that a combustion space is provided between the bottom and sides of the inner wall or retort shell on the one hand and said masonry structure on the other, said furnace retort having means for supplying a heating medium to the combustion space and also having supporting plates with flat horizontally extending tops and a saddle movably supported on each plate for locally supporting the inner wall construction, the plates and saddles being protected in each set from the heat by a masonry casing and the encased sets being arranged in spaced relationship.

14. A furnace-retort having an inner wall or retort shell, a masonry construction providing a refractory floor below the inner wall or retort shell and also side walls, inwardly extending side roof members, the construction being such that a combustion space is provided between the inner wall or retort shell on the one hand and said masonry construction and said side roof members on the other, and means for supplying a heating medium to the combustion space,

- 5 said furnace-retort having supporting plates with flat horizontally extending tops thereupon arranged in spaced relationship below the furnace, having a saddle movably 10 mounted on each plate and serving to locally support the inner wall or retort shell, and also having refractory means extending from the floor to the under side of the inner wall or retort shell and surrounding 15 each saddle.
15. A furnace-retort of the class described comprising supporting plates spaced from each other but arranged in a row, a saddle on each plate, a longitudinally extending 20 retort shell locally supported by each of said saddles, and a masonry construction providing a combustion space between the shell and the masonry construction, which masonry construction has portions surrounding 25 each of said plates and its saddle and extending upwardly to the bottom of the retort shell so as to protect the plates and saddles from the products of combustion, the masonry construction being so shaped 30 and positioned that a space is left between adjacent sets of plates and saddles whereby the products of combustion will have access to a substantial portion of the bottom of the retort shell.
- 35 16. A furnace-retort of the class described comprising saddles arranged in a row, supports for the saddles, each saddle being supported in a manner whereby in functioning it moves relative to its support, a retort shell receiving local support from said saddles, and a masonry construction providing a combustion space between the shell and the masonry construction, which masonry construction has portions surrounding each of 40 said saddles and extending to the bottom of the retort shell thus protecting the plates and saddle from the action of the products of combustion, the masonry construction being such that a space is left between adjacent 45 saddles whereby in the spaces the products of combustion will have access to the bottom of the retort shell.
- 50 17. A furnace-retort having a masonry construction providing a floor, side walls and end walls, a retort shell extending from end wall to end wall and located in the space between the side walls, and supports for the retort shell, which supports are arranged along the retort shell and are spaced from 55 each other, there being a combustion space between said retort shell on the one hand and said masonry construction on the other, the side walls having at the upper portions removable arched side roof sections carrying 60 gas burners.
- 65 18. A furnace-retort having masonry providing side walls, and a retort shell located in the space between the side walls, there being a combustion space between said retort shell and said masonry, the side walls hav-
- ing removable side roof sections provided with means for supplying gas and air to the combustion space.
- 70 19. A furnace-retort having masonry providing side walls, and a retort shell extending from end wall to end wall and located in the space between the side walls, there being a combustion space between said retort shell on the one hand and said masonry construction on the other, the masonry construction 75 having at the upper portions removable roof sections carrying gas burners.
- 80 20. A furnace-retort having a tubular wall or retort shell mounted in a masonry construction and extending from an end wall to an end wall thereof, said masonry construction having a floor portion and side walls, from which floor portion there extend supports located along and below the central longitudinal portion of the bottom of 85 the retort shell, said side walls having at the upper portion thereof arched members comprising outer castings holding therein refractory material and serving to bridge the space between each of the side walls and the 90 retort shell whereby there is completed the combustion space which is defined by the retort shell on the one hand and the masonry construction including the arched members on the other, each of said arched members 95 having burners for supplying a homogeneous mixture of proportioned gas and air to the interior of the combustion space, said masonry construction also having along the lower part of each side a longitudinally extending waste gas duct, which waste gas ducts are connected by a horizontally but transversely extending flue, said masonry construction also providing openings or passageways whereby the products of combustion 100 can pass from the combustion space to said ducts.
- 105 21. A furnace-retort having an inner wall or retort shell mounted in a masonry construction and extending longitudinally from an end wall to an end wall thereof, said masonry construction also having a floor portion and side walls, from which floor portion there upwardly extend supports located along and below the central longitudinal portion of the inner wall or retort shell, said side walls having at the upper portion thereof side roof members comprising holding castings carrying refractory material, which side 110 roof members bridge the space between each of the side walls and the inner wall or retort shell whereby there is completed the combustion space which is defined by the inner wall or retort shell and the masonry construction, 115 each of said side roof members having a burner for supplying a mixture of gas and air to the interior of the combustion space.
- 120 22. In combination, a furnace-retort, a pre-heater, means providing a waste heat flue that receives products of combustion from 125
- 130

the combustion space of the furnace of the furnace-retort and that conducts said products of combustion to the preheater, means for conducting and conveying dried material from the delivery portion of the preheater to the interior of the retort of the furnace-retort, the furnace-retort having a longitudinally extending inner wall or retort shell, within which the dried material is received, means for agitating or mixing the charge in the retort shell and for conveying the charge longitudinally from the charging end to the discharging end, and masonry on the exterior of said inner wall or retort shell, 15 the retort shell and masonry being constructed so that a combustion space is provided on the exterior of the retort shell and within the masonry, the preheater comprising a tubular receptacle or heating drum in which 20 the material to be dried and the products of combustion are received and from which the dried material is delivered, the construction being such that the tubular receptacle or the drum is supported independent of the 25 furnace-retort structure.

23. In combination a furnace-retort having a longitudinally extending inner wall or retort shell with means for agitating or mix-

ing the charge in the retort and for conveying the charge longitudinally from the charging end to the discharging end of the retort shell, masonry on the exterior of said inner wall or shell, the inner wall and masonry being constructed so that a combustion space is provided on the exterior of the inner wall 30 and within the masonry, a preheater comprising a rotary tubular receptacle or rotary heating drum in which the material to be dried and the products of combustion are received and from which the dried materials 35 are delivered, means providing a waste heat flue or flues extending upwardly from the combustion space of the furnace of the furnace-retort to the preheater whereby products of combustion can pass from the combustion space to the tubular receptacle or heating drum, and means for conducting and conveying the dried material from the delivery portion of the receptacle or drum to the interior of the inner wall or retort shell, the 40 construction being such that the drum is supported above and independent of the furnace-retort structure.

This specification signed this 30th day of July, A. D. 1919.

CHARLES E. RICHARDSON.
